CLAIM

The ornamental design for a golf club set, as shown and described.

DESCRIPTION

FIG. 1 is a perspective view of a golf club set, each club in the set having our design;

FIG. 2 is a front view of the golf club set of FIG. 1;

FIG. 3 is a rear view of the golf club set of FIG. 1;

FIG. 4 is a left side view of golf club set of FIG. 1;

FIG. 5 is a right side view of the golf club set of FIG. 1;

FIG. 6 is a top view of the golf club set of FIG. 1; and,

FIG. 7 is a bottom view of the golf club set of FIG. 1.

Portions of the golf club set shown in broken lines forms no part of the design claimed.

Portions of the design shown with stippling indicate a contrasting shade or color from non-stippled portions.
